TO WEAVER MANUFACTURING COMPANY, OF SPRINGFIELD, ILLINOIS, A CORPO-
RATION OF ILLINOIS.

TIRE-REMOVING APPLIANCE.

1,341,730.

Specification of Letters Patent.

Patented June 1, 1920.

Original application filed October 6, 1916, Serial No. 124,011. Divided and this application filed July 14, 1919. Serial No. 310,863.

To all whom it may concern:

Be it known that we, IRA A. WEAVER and JOHN STERNAMAN, both citizens of the United States, residing at Springfield, in the 5 county of Sangamon and State of Illinois, have invented certain new and useful Improvements in Tire-Removing Appliances, described and claimed in the following specification.

10 The pneumatic tire-casings in common use not infrequently become adhered, rusted, or so-called "frozen" to their vehicle-wheel metal-rims and it is with some difficulty that the two are separated unless some special 15 means are employed to break them apart. The present invention relates to simple and efficient means for breaking such undesirable unions and thereby assist in removing the tire-casing from the associated rim. To 20 this end, the preferred embodiment of the invention comprises a suitable support or standard equipped with means for quickly centering and fixedly holding the rim and casing, and a radial arm above the centered 25 rim adapted to revolve about its axis, such arm being adjustable as to height and carrying a curved arm reaching around to the under side of the casing and there equipped with an inclined roller adapted to ride on 30 the bottom or under face of the casing and raise it free from the flange of the rim during the revolution of the radial arm about the rim's axis. More specifically, it is desirable to provide the radial arm with a 35 sliding sleeve adjustable lengthwise thereon and hinge the curved arm thereon at a point inwardly of the point of action of the roller on the casing, whereby such roller will experience no tendency to undesirable out- 40 ward displacement but will tend to continue its engagement with the casing at its inner portion, that is, adjacent to the rim.

Although the invention is susceptible of a variety of embodiments, it is unnecessary to 45 fully describe and illustrate more than one in order to give a full understanding of the invention both from its structural and functional standpoints. Accordingly, we have illustrated a preferred and desirable 50 embodiment of the invention in the accompanying drawings forming a part of this

specification and throughout the views of which like reference characters refer to the same parts.

In these drawings:

55

Figure 1 is a fragmentary central vertical section through the appliance illustrating its action on a pneumatic tire-casing; and

Fig. 2 is a plan view of the structure showing the radial arm and the parts which 60 it carries in a different angular position.

Referring to these drawings, it will be readily understood that the appliance includes a hollow, upright standard or post 19 with a base 20, the standard at its top 65 being provided with a cap-piece 21 having three radiating rim-supporting arms 22, 23, 24, each provided on its top face with a lengthwise undercut groove 25 accommodating a base-portion 26 of an upstanding 70 sliding rim-clamping jaw 27, the three jaws being adapted to simultaneously expand and contract and designed to engage the inner surface of a vehicle-wheel rim, center it, and fixedly hold it. To this end each jaw 75 base has a threaded aperture 28 receiving a threaded shaft 29 located in the corresponding groove 25 and having a bearing at 30 for its inner end. Each of such shafts at its inner end is equipped with a bevel pinion 80 31 in mesh with the teeth of a common, centrally-disposed, horizontal gear 32 having a cylindrical bearing 33 on the hub 34 of member 21 and a flat bearing at 35 on the same part. One of these shafts is longer 85 than the others, its outer end portion having a bearing 36 and an operating-handle 37. Thus, by turning such handle, the three rim-centering and clamping jaws may be moved in or out in unison, as will be readily 90 understood.

Hub 34 affords also a central bearing for an upright rotary and vertically-adjustable shaft 40 having its upper end 41 bent over horizontally, thus constituting a radial arm 95 revoluble about the center or axis of the rim, held by the jaws. To adjust this shaft so that its horizontal portion 41 will be moved vertically to different heights, that is, toward and from the plane of the rim, 100 a lever or handle 42 is fulcrumed at 43 on brackets 44, and projects through an aper-

ture 45 into the interior of the standard or post where it is operatively connected to the lower end of the shaft. This connection is conveniently accomplished by making the 5 inner end of the lever bifurcated or forked to straddle the shaft and equipping such end with a pin 46 taking into a circular or annular groove 47 in the shaft. To maintain this radial arm 41 at the desired ad- 10 justed height, the handle 42 is supplied with a pivoted dog or catch 48 which co-operates with the notches of a stationary, curved, sector or arcuate arm 49 depending from the corresponding spider-arm 22.

15 Arm 41 is fitted with a sleeve 50 slideable lengthwise thereon and adapted to be held or maintained in proper position by a set-screw 51 having a suitable turning handle 52. To prevent injury to the arm and to 20 hold the sleeve from turning, the former is desirably provided with a longitudinal groove 53 into which the set-screw projects.

The upper outer end portion of the sleeve 25 has an ear 54 transversely apertured at 55 to form a hinge bearing for the lateral shank 56 of a curved or goose-neck arm 57 shaped to extend around the rim and tire to the under-side of the latter. Such 30 lower end of the bent or curved arm has an inclined, beveled, anti-friction roller 58 rotatably mounted thereon, the face of the roller being adapted to engage and raise the tire casing from the lower flange of the 35 rim, as is fully illustrated, thus assisting the removal of the casing from the rim. This conical roller frees the tire casing or shoe from the rim by a lifting or upward displacing action during the revolution of 40 the radial arm on which it is mounted about the axis of the rim. As a means for preventing catching and tearing of the casing or the flap in the split locking-ring groove of arm of this sort, such groove 45 is temporarily provided with a filler or cover 59 of suitable shape. It will be noted that the pivot or hinge point of the goose-neck arm is inside the point of the engagement of the roller 58 with the tire-casing, 50 and that the mounting of the roller is such that it is inclined with relation to the flat web of the rim. This construction tends to cause the roller to hug the face of the tire-rim closely while forcing the casing upwardly, thus eliminating the possibility of 55 damaging such part of the tire.

The operation of the appliance occurs practically as follows:

The rim and its casing are placed on the 60 three radiating, supporting arms during the contracted condition of the jaws 27. Thereupon, by turning the handle 37, the jaws are simultaneously expanded, causing the centering and firm clamping of the rim in 65 such position. The shield 59 having been

put in place, the goose-neck arm and its roller having been brought to proper position, and the sleeve having been adjusted to the correct location on the radial arm and locked in place, the operator presses lever 70 42, thus elevating roller 58 by raising the various elements which carry it. Then while the parts are locked in this proper height position by catch 48 entering one of the notches of the sector 49, the radial 75 arm 41 is revolved about the axis of the centered rim. Such travel of roller 58 progressively lifts or raises the casing from the lower flange of the rim and owing to the disposition of the roller and its shape, 80 and the form of the curved arm 57 and the location of its hinge mounting, the anti-friction roller tends to remain close to the rim and elevates the casing without injury to the latter. After one complete revolution of arm 41, or even before, it may be further elevated at intervals and the rotation continued until the tire-casing is entirely free from the rim or sufficiently so 85 that it can be readily taken off. 90

The invention is not limited and restricted to the precise and exact structural details illustrated and described, because these may be modified within comparatively wide limits without departure from the substance 95 of the invention and without the sacrifice of any of its substantial benefits and advantages.

This application is a division of our earlier application for tire changing machines, Serial No. 124,011, filed October 6, 1916.

We claim:

1. In a tire remover, the combination of means to fixedly hold a vehicle-wheel-rim, 105 and a member mounted to rotate about the axis of the rim and engage the opposite side of the tire-casing adjacent to the rim to assist in freeing the tire-casing from the rim, substantially as described.

2. In a tire remover, the combination of means to fixedly hold a vehicle-wheel rim, a member mounted to rotate about the axis of the rim in a plane parallel to that of the rim and to engage the opposite side of the tire-casing adjacent to the rim to assist in freeing the casing from the rim, and means to adjust said member toward and from the plane of the rim, substantially as 115 described.

3. In a tire remover, the combination of means to fixedly hold a vehicle-wheel rim in substantially-horizontal position, and a member mounted to rotate about the axis of the rim and engage the under side of 125 the tire-casing adjacent to the rim to assist in freeing the casing from the rim, substantially as described.

4. In a tire remover, the combination of means to fixedly hold a vehicle-wheel rim 130

in substantially-horizontal position, a radial arm mounted to rotate about the axis of and above the rim, and a member carried by said arm shaped to extend around the tire-casing on the rim and adapted to engage its under face to assist in freeing the casing from the rim, substantially as described.

5 5. In a tire remover, the combination of means to fixedly hold a vehicle-wheel rim in substantially - horizontal position, a radial arm mounted to rotate about the axis of and above the rim, means to adjust said radial arm toward and from the plane of the rim, and a member carried by said arm shaped 10 to extend around the tire-casing on the rim and adapted to engage its under face to assist in freeing the casing from the rim, substantially as described.

10 6. In a tire remover, the combination of means to fixedly hold a vehicle-wheel-rim in substantially - horizontal position, a radial arm mounted to rotate about the axis of and above the rim, means to adjust said radial arm toward and from the plane of the rim, a 15 sleeve adjustable lengthwise on said arm, and a member carried by said sleeve shaped to extend around the tire-casing on the rim and adapted to engage its under face to assist in freeing the casing from the rim, substantially as described.

20 7. In a tire remover, the combination of means to fixedly hold a vehicle-wheel rim in substantially-horizontal position, a radial arm mounted to rotate about the axis of and above the rim, means to adjust said radial arm toward and from the plane of the rim, a 25 sleeve adjustable lengthwise on said arm, a member shaped to extend around the tire-casing on the rim hinged to said sleeve and adapted to engage the under side of the tire to assist in freeing the casing from the rim, substantially as described.

30 8. In a tire remover, the combination of a standard, a plurality of jaws adapted to engage and fixedly hold a vehicle-wheel rim in substantially-horizontal position, means to simultaneously expand or contract said jaws, a radial arm mounted to rotate about the axis of and above the rim, means to adjust said radial arm toward and from the plane of the rim, a sleeve adjustable lengthwise on said arm, means to lock said sleeve in adjusted position on said arm, a member hinged to said sleeve and shaped to extend 35 around the tire-casing on the rim, and a roller on the lower end of said member adapted to engage the under face of the tire-

casing to assist in freeing the same from the rim, substantially as described.

9. In a tire remover, the combination of means to hold a vehicle-wheel rim, a radial arm adapted to revolve about the axis of the rim, a goose-neck arm carried by said radial arm adapted to extend around the rim and its tire-casing, and a roller on said goose-neck arm adapted to engage the tire-casing on the side opposite said radial arm and to assist in freeing the casing from the rim, substantially as described.

10. In a tire remover, the combination of means to hold a vehicle-wheel rim, a radial arm adapted to revolve about the axis of the rim, a goose-neck arm carried by said radial arm adapted to extend around the rim and its tire-casing, and a roller on said goose-neck arm adapted to engage the tire-casing on the side opposite said radial arm and to assist in freeing the tire-casing from the rim, the plane of said roller being inclined to the plane of the rim, substantially as described.

11. In a tire remover, the combination of means to hold a vehicle-wheel rim, a radial arm adapted to revolve about the axis of the rim, a goose-neck arm hinged to said radial arm and adapted to extend around the rim and its tire-casing, and a roller on said goose-neck arm adapted to engage the tire-casing on the side opposite the radial arm and to assist in freeing the tire-casing from the rim, the hinge mounting of said goose-neck arm on said radial arm being nearer the axis of the rim than the point of contact of the roller with the tire-casing, substantially as described.

12. In a tire remover, the combination of means to hold a vehicle-wheel rim, a radial arm adapted to revolve about the axis of the rim, a goose-neck arm hinged to said radial arm and adapted to extend around the rim and its tire-casing, and a beveled roller on said goose-neck arm adapted to engage the tire-casing on the side opposite said radial arm to assist in freeing the tire-casing from the rim, the plane of said roller being inclined to the plane of the rim, the hinge mounting of the goose-neck arm on the radial arm being nearer the axis of the rim than the point of engagement of the roller with the tire-casing, substantially as described.

IRA A. WEAVER.
JOHN STERNAMAN.
